UNITED STATES PATENT OFFICE.

JOHN P. NEFF, OF EAST ORANGE, NEW JERSEY, ASSIGNOR, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,031.

Specification of Letters Patent.

Patented May 4, 1915.

Application filed May 25, 1907. Serial No. 375,627.

To all whom it may concern:

Be it known that I, JOHN P. NEFF, a citizen of the United States, and a resident of East Orange, Essex county, State of New Jersey, have invented certain new and useful Improvements in Locomotive-Boiler Furnaces, of which the following is a full, clear, and exact description, such as will enable others skilled in the art to which it applies to make and use the same.

My invention relates to improvements in locomotive boiler furnaces and has particular reference to improvements in arches for such furnaces. Its object is to improve the operation of locomotive boiler furnaces; and particularly to increase the efficiency and the durability of the front arches or baffles of such furnaces or fireboxes.

The special purposes of my invention are, to more surely and to a greater extent hold back or retard the products of combustion, including the solids, which rise from the fire;—to more certainly and effectively admix the combustibles while in the fire chamber and before they rise into the combustion chamber of the firebox; and, to insure better combustion and a more uniform distribution of the heat throughout the firebox. Further objects and results of my invention will appear hereinafter.

The principle of my invention and the best mode of applying the same and the nature and the details of the invention as distinguished from others will be clearly understood upon reference to the accompanying drawings, forming a part of this specification, and in which:—

Figure 1 is a vertical longitudinal section of a locomotive boiler furnace embodying my invention, the section being substantially on the line X—X of Fig. 2;—Fig. 2 is a horizontal section, on the line Y—Y of Fig. 1, viewed from below;—Fig. 3 is a vertical transverse section, on the line Z—Z of Fig. 1;—Fig. 4 is a sectional detail on the line U—U of Fig. 1;—and, Fig. 5 is a detailed longitudinal section, on the line V—V of Fig. 2.

The drawings disclose a firebox or furnace proper, contained within a locomotive boiler and surrounded by the usual water legs or spaces. As therein shown, 5, is the crown sheet of the firebox;—6, is the rear sheet, containing a door opening 6';—7, 7, are the side sheets;—3, is the flue sheet.

The flues, 4, as usual, are secured in and lead forward from the flue sheet. The bottom of the firebox contains a fuel grate 2. As best shown in Fig. 1, I interpose an upwardly and rearwardly inclined front arch or baffle between the flues, 4, and the bottom of the firebox, the same dividing the firebox into a fire chamber, A, and a combustion chamber, B. An arch, thus positioned, baffles and prevents the direct flow of the products of combustion from the grate, 2, to the flues, 4. In constructing my novel refractory arch I employ a plurality of longitudinal water circulating arch tubes, 8, and a number of refractory bricks, 9, 10, and, 11, supported by said tubes, 8. The arch tubes extend upwardly and rearwardly, preferably from the lower part of the flue sheet, 3, to the upper part of the rear sheet, joining the front and rear water legs of the boiler. In that form of my invention which is depicted in the drawings, there are four longitudinal inclined arch tubes, 8, and five longitudinal rows of refractory bricks, said longitudinal rows corresponding to the spaces defined by said tubes. I thus form a substantially imperforate, inclined arch or baffle which extends, preferably, from side to side of the firebox and which rises to about the middle thereof. In some cases I provide cinder openings, 12, near the lower end of the arch, through which cinders that lodge on the top of the arch may pass back into the fire chamber.

The proportions, joints, and relations of the typical bricks, 9, 10, 11, are clearly disclosed in Figs. 2, 3 and 4; and, except as to the particular features and functions herein set forth, are fully defined in Letters Patent of the United States No. 904,494. My invention is not specially concerned with such details but instead has to do with the form and operation of the bottoms of locomotive furnace arches, and is especially directed to the improvement of the large units or bricks which characterize arches that possess the general advantages described in aforesaid patent. In conformity with the best prior practice, I prefer that the top of my arch shall be substantially smooth, that is, offer few if any obstructions to the passage of either the solids or the gases of combustion. But, contrary to prior practices, I do not use arch bricks that have smooth bottoms. Instead, I roughen or cor-

rugate the bottom of the arch in such manner that it obstructs both the transverse and the longitudinal movements of the products of combustion beneath the arch, and effectively retards the solids and mixes the gases.

The bricks are best left smooth where they contact the tubes, 8, in order that they may rest securely thereon; but I roughen or corrugate those parts of the arch bottom which bridge the spaces defined by the tubes. As indicated in the drawings the corrugations may be variously formed. Thus, as well shown in Figs 2 and 3, the middle spaces or portions of the arch bottom are corrugated by providing the bricks, 9, and, 10, with relatively deep pits or recesses, *a*; and, preferably, similar pits or recesses are provided in the marginal portions of the arch bottom by providing a number of transverse ribs or projections, 11', upon the bottoms of the bricks, 11.

The many transverse portions, *d*, having preferably inclined under or inner surfaces, *b*, *c*, and also the sides, 11'', of the ribs, 11', 25 constitute effective obstructions to the longitudinal flow of the products of combustion beneath the arch, and the lateral ends of the pits or recesses and also the sides of the tubes, 8, effectively baffle or obstruct the transverse movements of the products. Also, 30 the cells or pits, in themselves, tend to retard and divert the products. The cells, pits, recesses, or cavities here shown in my novel arch, though arranged in both longitudinal and transverse rows, are separate and distinct and do not communicate, being open 35 only at the bottom. As best shown in Fig. 3, the bottom of the arch is longitudinally channeled, the tubes, 8 forming the lower sides of such channels. As the products rise beneath the arch they are divided or distributed into longitudinal streams by these channels, and, while traversing the grooves or channels, the products are retarded and 40 the streams are effectually broken up by the corrugated, pitted or recessed tops of such channels. Thus the products of combustion, meaning all which rise from the bottom of the firebox, are retarded and thoroughly distributed, deflected and admixed, many of 45 the solids, such as cinders, being thrown back upon the grate. Such arches are strong, durable and dependable, and are much lighter than arches of the kind shown in 50 aforesaid patent, and much more efficient, greatly improving the operation and performance of the locomotive boiler furnaces which contain them.

Where a rear arch, such as the arch, 13, 55 (Figs. 1 and 2) is required in the firebox, I provide the same with distinct, non-communicating pits or recesses, *e*, and deflecting surfaces, *e'*, like those of the above described front arch.

Having thus described my invention I

claim as new and desire to secure by Letters Patent:

1. A locomotive boiler and its contained firebox and flues, in combination with a substantially imperforate arch interposed between said flues and the bottom of the firebox, said arch comprising a plurality of upwardly and rearwardly inclined longitudinal water circulating tubes and refractory bricks supported thereby, the bottoms of said bricks together with said tubes forming a plurality of longitudinal channels that divide the products of combustion into longitudinal streams and the tops of said channels containing many distinct non-communicating cells or recesses which retard the products of combustion and break up said streams.

2. A locomotive boiler and its contained firebox and flues, in combination with a substantially imperforate arch interposed between said flues and the bottom of the firebox and extending from side to side thereof, said arch comprising a plurality of upwardly and rearwardly inclined longitudinal water circulating tubes and rows of refractory bricks supported thereby, the bottoms of said bricks together with said tubes forming a plurality of longitudinal channels spaced from side to side of the firebox and which divide the products of combustion into longitudinal streams, and the tops of said channels containing many distinct non-communicating cells or recesses that retard the products of combustion and break up said streams.

3. A locomotive boiler and its contained firebox and flues, in combination with a plurality of inclined longitudinal arch tubes, in said firebox, a plurality of transverse and longitudinal rows of refractory bricks supported by said tubes, the bottoms of said bricks together with said tubes forming a plurality of longitudinal channels that divide the products of combustion into longitudinal streams, and the bottoms of said bricks containing corresponding rows of recesses and projections that retard the products of combustion and break up said streams.

4. A locomotive boiler and its contained firebox and flues, in combination with an upwardly and rearwardly inclined arch interposed between said flues and the bottom of the firebox and comprising a number of longitudinal water circulating tubes and a plurality of longitudinal rows of refractory bricks supported by said tubes, the bottoms of said bricks together containing a plurality of transverse and longitudinal rows of distinct non-communicating recesses which retard the products of combustion and break up the longitudinal and transverse streams thereof.

5. A locomotive boiler and its contained

- firebox and flues, in combination with a substantially imperforate arch interposed between said flues and the bottom of the firebox, said arch comprising a plurality of upwardly and rearwardly inclined longitudinal water circulating tubes and refractory bricks supported thereby, the bottoms of said bricks together with said tubes forming a plurality of longitudinal channels that divide the products of combustion into longitudinal streams and the tops of said channels being corrugated and acting to retard said products and break up said streams. 6. A locomotive boiler and its contained firebox and flues, in combination with a substantially imperforate refractory brick arch interposed between the flues and the bottom of the firebox, the bottom of the arch presenting a plurality of longitudinal channels which divide the products into longitudinal streams and the tops of said channels being formed with obstructions adapted to retard said products and break up said streams. 7. A locomotive boiler and its contained firebox and flues, in combination with a substantially imperforate refractory arch interposed between the flues and the bottom of the firebox, the bottom of said arch being formed to divide the products of combustion into longitudinal streams and containing a plurality of longitudinal rows of distinct non-communicating recesses adapted to retard said products and break up said streams. 8. A locomotive boiler and its contained firebox and flues, in combination with a substantially imperforate refractory brick arch interposed between the flues and the bottom of the firebox, the bottom of the arch presenting a plurality of longitudinal channels which divide the products into longitudinal streams and the tops of said channels containing rows of distinct non-communicating recesses presenting obstructions adapted to retard said products and break up the longitudinal and transverse streams thereof. 9. A locomotive boiler and its contained firebox and flues, in combination with a refractory brick arch interposed between the flues and the bottom of the firebox, the bottoms of the bricks together containing a plurality of transversely spaced longitudinal rows of distinct non-communicating recesses separated by transverse and longitudinal deflecting walls and adapted to retard the products of combustion and break up the longitudinal and transverse streams thereof. 10. A locomotive boiler and its contained firebox and flues, in combination with a substantially imperforate refractory brick arch interposed between the flues and the bottom of the firebox, the bottoms of the bricks together containing a plurality of transversely spaced longitudinal rows of recesses and being thus adapted to retard the products of combustion and break up the streams thereof.
- In testimony whereof, I have hereunto set my hand this 17th day of May, 1907, in the presence of two subscribing witnesses.
